UNITED STATES PATENT OFFICE.

MARSHALL M. BISHOP, OF EVANS' MILLS, NEW YORK, ASSIGNOR OF TWO-THIRDS TO FREDERICK E. CROISSANT, OF ANTWERP, AND HORACE W. SMITH, OF STERLINGVILLE, NEW YORK.

CAR-COUPLING.

SPECIFICATION forming part of Letters Patent No. 616,881, dated January 3, 1899.

Application filed February 11, 1898. Serial No. 670,001. (No model.)

To all whom it may concern:

Be it known that I, MARSHALL M. BISHOP, of Evans' Mills, in the county of Jefferson and State of New York, have invented new and useful Improvements in Car-Couplings, of which the following, taken in connection with the accompanying drawings, is a full, clear, and exact description.

The object of my invention is the production of a car-coupling of simplified construction absolutely operative under all conditions, wherein duplicate-like coupling-heads are utilized, in which a knuckle-like hook or engaging arm is utilized, a device which is positive and reliable in operation, wherein in one integral formation a knuckle, tongue, and trailer pivotally operative in conjunction with the coupler-head is employed, a coupling or locking pin also operative therewith, and in the employment of certain details of construction imparting increased efficiency and reliability of operation to the coupler.

Referring to the drawings accompanying this specification, Figure 1 is a top plan of one of the pair of companion-like opposing coupling-heads entering into my construction of a car-coupling, the pin being represented in a position for lockingly holding the coupling-heads in a coupled attitude; Fig. 2, a side elevation of said antagonistic coupler-head in a locked or coupled position; Fig. 3, a vertical longitudinal section taken along dotted line *w w*, Fig. 1, of the drawings, as delineating my device in a coupled position; Fig. 4, a vertical longitudinal section taken along the aforementioned line in Fig. 1, illustrating my invention as uncoupled and the locking-pin resting or riding upon the trailer of the knuckle-hook; Fig. 5, a horizontal longitudinal section taken along dotted line *x x*, Fig. 2, showing my coupling in a locked or coupled condition; and Fig. 6, a sectional view on a corresponding plane, same figure, illustrative of my device as uncoupled or open and the locking-pin resting on the trailer of the tongue or tail appertaining to the knuckle-hook forming an essential feature of my device.

Corresponding letters and ordinals desig-

nate like parts throughout the views of the drawings.

My invention consists in the novel features of construction, coöperativeness, and combination, and manner of operation hereinafter described and which are specifically set forth in the annexed claims, reference being had to the accompanying drawings, utilized in connection with my specification. Its construction and operation are as now stated.

1 indicates one of a pair of corresponding coupling-heads and integral draw-bar portions, but one of the pair being illustrated for the reason that such is all-sufficient for proper exemplification of my invention.

A specifically designates the recessed or chambered coupling-head of one of the antagonistic members appertaining to my device, and A' a fragmentary portion of the integral draw-bar thereof, while B denotes the knuckle-hook member, pivotally mounted at the forward portion of the coupling-head by means of a vertical pin or bolt *a*, passing through the body portion of the knuckle-hook by means of an alining-orifice or bolt-hole *a'*, which aforesaid pin is provided with a head adapted to rest upon the top surface of the coupler-head, its stem or shank portion passing through circular holes *a'' a''* in the horizontal ear-like portions of the head, alining with the hole *a'* in the knuckle-hook member when same is located in place, said knuckle member occupying the intermediate space between the ears *b b* mentioned.

c denotes a vertical pin-hole through the hook or grapple portion B' of the knuckle-hook member, and *c'* a horizontal slot or recess midway the height of such knuckle-hook, thereby adapting the utilization of an ordinary coupling pin and link in instances where a contiguous car awaiting coupling is not provided with a coupler-head and mechanism of my type.

Rearwardly and at an angle to the projection of the hook part B' of the knuckle-hook member there extends backward a suitable distance a tail or tongue portion B'', terminating in a trailer extension B''' of segmental contour longitudinally and extending at an an-

gle to the tail, and its projection being in an adverse direction to that of the hook proper of the knuckle-hook member, yet all disposed upon a substantially like horizontal plane, 5 which tail and its trailer are integrally formed with the central body and hook of the afore-referred-to pivotal member, the construction and arrangement thereof being clearly shown in the figures of the drawings.

10 2 is denotive of a recess or cavity extending into the coupler-head A from its front face and of requisite width and depth, which said horizontal cavity or chamber has a continuation 2' of elongated and segment-like contour longitudinally, which auxiliary cavity or recess is preferably at its top boundary coincident with the top plane of the cavity 2 and its bottom located upon a somewhat higher horizontal plane, said aforesaid conjoint and 15 connecting cavities or chambers being receptive of the trailer and tail portions of the knuckle-hook member B, the curvilinear cavity receiving the trailer B''' and the outer cavity the tail B'', there being provided ample leeway for the thrust or travel of said parts thereby within the hollowed interior of the coupling-head.

18 The rear portion of the trailer B''' of the knuckle member has a raised or cam-acting 30 portion C integral with the remainder of said trailer, which cam portion is as to its face of -like contour longitudinally, its operative face comprising slight inclines d d, united by a slight horizontally-level surface d'. The remaining depressed top face of the trailer is 35 level and its bottom edge substantially so.

40 3 3' indicate a vertical passage or bore through my coupler-head A contiguous the forward edge or face of its swelled body portion and being located sufficiently away from the front to insure of there being that amount of metal between it and the forward edge as will insure all needed strength against the strain that may be entailed by a gravity 45 coupling pin or bolt whenever same is thoroughly seated to utmost limit within the receptive pin-hole 3 3' priorly mentioned.

48 As is discernible, the passage or pin-hole 3 3' is broken from continuity by the cavity 50 2. However, the upper portion 3 and the lower portion 3' are in alinement, as shown. This pin-hole may be circular, as shown, or square in cross-section, according to the transverse contour of the coupling or locking 55 pin employed. This gravity locking pin or bolt of requisite weightiness I designate by the ordinal 4 and comprising an elongated shank or stem e, a flange-like head e', and an eye portion e'', projecting briefly above its 60 head, and pivotally connected with said eye portion I may provide any satisfactory or suitable pin-manipulating lever or rod 5, leading to the side or end of a car and thereat erected and arranged in any manner preferred.

65 At a sufficient distance rearward of the pin or bolt 4 there is pivotally erected upon the top of the draw or coupling head portion an

L-like dog or trip-lever D, pivotally secured at the rear of its horizontal base portion to ears f f, arising from the coupler-body and 70 pivotally retaining the interposed extremity of the dog aforesaid by means of a pivot-pin g.

75 The perpendicular arm-like portion of aforesaid dog terminates at its top in a bent finger h, adapted, as is obvious, to under certain conditions engage the under side of a contiguous portion of the head e' of the pin or bolt 4.

80 Beneath the central portion of the base extension of the dog or trip-lever D and just forward of the lugs or ears f f there is a moderate-sized cavity or recess i of rectangular shape, extending from the top surface of the coupler-body such a degree as is necessary for 85 the easy occupancy thereof of a square-like head k of a lug E, comprising, in conjunction with such head, a cylindrical stem or shank l, rounded at its bottom, as at m, which stem, depending integrally from the head a requisite degree, loosely occupies an aperture or bore n of smaller diameter than the cavity i, wherefrom it downwardly extends, communicating with the chamber 2', occupied by the trailer of the knuckle - hook under certain 95 conditions. As is discernible, there is allowable required rise and fall of the lug E for the carrying out of the function designed for. Perpendicularly through the base of the dog member and meshing with the threaded bore 100 through which it penetrates is an adjusting or regulating screw F, having a slotted head and the end of its stem abutting the top of the vertically-movable lug E, the function of such regulating-screw being to regulate the 105 degree of play of the dog member.

110 The pointed projection p of the coupler-head acts as a buffer when two antagonistic heads are in coupled relation.

115 The operation of my device is, in brief, as follows: When the knuckle-hook member is in that position whereby it is retained lockingly by the gravity-pin—to wit, in a coupling attitude—the lug member rests upon the level top surface of the trailer extension of 115 such knuckle member, and the dog is obviously in an attitude admitting its engagement with the under side of the flange-like head of the gravity locking-pin, when same may be lifted by the operator requisite height to 120 clear the trailer of the knuckle-hook and retained at such location by the finger or lip of the pivoted dog, and when so upheld permitting of the forward swing of the knuckle-hook member and uncoupling from an antagonistic coupler-head, such movement entailing the raising of the lug member by reason of the action of the cam portion of the trailer and causing the swinging away and clearing of the dog from the head of the gravity-pin, 125 permitting said pin's precipitation and the resting thereof on the level face of the trailer and continuing to ride or rest thereon while the knuckle-hook member moves outward, 130

- assuming a position for coupling—*i. e.*, a receptive attitude for engagement with a like portion of an opposing coupling-head located on another car. Evidently when contact is had the blow entails the instantaneous rearward travel of the knuckle-hook member in a pivotal manner of progression and to such degree as to carry the angular junction of the trailer and tail sufficiently rearward to clear the orifice in the coupler-head provided for the gravity locking-pin, permitting said pin, if not priorly raised and suspended above the member, to be through gravity instantaneously precipitated downward in front of the contiguous portion of the knuckle-hook member and occupying the pin-holes in the head, serving to retain the knuckle-hook in a coupling attitude. The lug invariably raises from the center.
- 20 The many evident advantages of my coupler are evident, especially to those versed in the construction of car-couplings.
- Having described my invention, what I claim as new, and desire to secure by Letters Patent, is—
1. A car-coupling comprising the head, and the pivoted knuckle-hook having the trailer, combined with the gravity-pin, the exposed pivoted dog mounted upon said head and adapted to engage the head of said pin and maintain the pin in an elevated position, and means for tilting said dog to release said pin in order that it may ride on and then descend in front of said trailer on the inward movement of the latter; substantially as set forth.
  2. In a car-coupling of the character described, the gravity locking-pin having the head, combined with the exposed pivoted dog adapted to engage said head when the pin is elevated and thus maintain the pin in its elevated position, and means for automatically releasing the dog from said pin upon the movement inward of the knuckle-hook member of the coupling; substantially as set forth.
  - 45 3. In a car-coupling, the knuckle-hook pivoted member having the inwardly-extending trailer whose upper surface presents a cam, combined with the gravity locking-pin, the exposed trip-dog pivoted upon the coupler-head and adapted to engage said pin and maintain the same in an elevated position, and the lug below said dog and above said trailer and adapted to be acted upon by said cam to move said dog; substantially as set forth.
  - 55 4. In a car-coupling, a recessed coupler-head,

a knuckle-hook member pivotally secured to the forward end, said pivotal member comprising a knuckle, tail and a trailer, the trailer adapted to occupy an elongated cavity in the coupler-head body, said trailer being of segment shape longitudinally and having a cam-acting protuberance, a lug capable of operation thereby, a dog adapted to movement by afóresaid lug, and a gravity locking-pin mov- 65 ably erected in advance of the dog and adaptable of engagement and release thereby, sub-stantially as described.

5. In a car-coupling, the knuckle-hook member having the segmental trailer, combined 70 with the gravity locking-pin whose vertical plane is in the path of said trailer, the trip-dog adapted to engage said pin and hold it in an elevated position, and means for releasing said dog and pin from one another so that 75 said pin may ride along and remain on the upper surface of said trailer during the outward and inward motion of said knuckle-hook member and descend below said trailer only upon the completion of the inward mo- 80 tion of said knuckle-hook member; substan-tially as set forth.

6. In a car-coupling the knuckle-hook mem-ber having the segmental trailer, combined 85 with the gravity locking-pin whose vertical plane is in the path of said trailer and whose upper portion is provided with a head, the pivoted trip-dog whose upper end is normally in the path of said head and automatically engages the latter when the pin is raised to 90 move said head above said upper end and thus tilt the said dog outward temporarily but permitting it to return by gravity to its normal position, and means for releasing said dog and pin from one another on the outward 95 movement of said knuckle-hook member so that said pin will during such movement ride on said trailer, the latter being of such form and extent that it prevents said pin from de-scending below the trailer except when the 100 knuckle-hook member is moved entirely in-ward; substantially as set forth.

In testimony whereof I have hereunto signed my name, in the presence of two at-testing witnesses, at Evans' Mills, in the 105 county of Jefferson, in the State of New York, this 22d day of November, 1897.

MARSHALL M. BISHOP. [L. S.]
